UNITED STATES PATENT OFFICE.

CHARLES E. ONGLEY, OF NEW YORK, N. Y., ASSIGNOR, BY MESNE ASSIGNMENTS, TO BUTTON SEWING ATTACHMENT COMPANY, A CORPORATION OF MAINE.

BUTTON-SEWING ATTACHMENT FOR SEWING-MACHINES.

No. 893,538.

Specification of Letters Patent.

Patented July 14, 1908.

Application filed March 17, 1906. Serial No. 306,499.

To all whom it may concern:

Be it known that I, CHARLES E. ONGLEY, a citizen of the United States, and a resident of the borough of Manhattan, in the county of New York and State of New York, have invented certain new and useful Improvements in Button-Sewing Attachments for Sewing-Machines, of which the following is a specification.

10 This invention relates to a button sewing attachment for sewing machines.

The organization of the invention primarily comprises means, by which either a two hole or four hole button can be sewed to a material, and in the latter case to be able to either sew the stitches diagonally across the button, or on the perimeter line joining the button holes of the button. The stitches diagonally across the button will overlap each other, and the stitches on the perimeter line will be consecutively adjacent to each other. These new technical effects are produced by moving the buttons in the requisite paths under the point of a needle of a sewing machine, and in the case of a two hole button it is reciprocated in a practically straight line under the point of said needle, said line being parallel to the line joining the holes of the button. With a four hole button it is approximately moved in a straight line diagonally across the button, parallel to the diagonal of the polygon formed by joining the holes of the button to sew a number of stitches, and then the button is moved in a line at right angles thereto, and also diagonally across the polygon formed by lines joining the holes of the button. When the stitches are to follow the perimeter as above described, the button is simply moved in directions parallel to such perimeter, while the stitches are formed.

Referring to the drawings; Figure 1 represents a front elevation of the invention, with a fragmentary view of a sewing machine to which it is attached; Fig. 2 shows a plan view of the invention, Fig. 3 is a partial section of Fig. 2 on the line 3, 3, Fig. 4 represents a fragmentary portion of Fig. 1 with some of the parts in changed positions, Fig. 5 is a left hand end view of Fig. 1, Fig. 6 shows a right hand end view of Fig. 1, Fig. 7 represents a bottom plan view of one of the clamping jaws, Fig. 8 shows a plan view of a portion of the clamping device, Fig. 9 shows a two hole button with its stitches, Fig. 10 shows a four

hole button with the stitches diagonally across the holes of the same, and Fig. 11 represents a four hole button with stitches passing through the successive holes in the button forming a polygon. 60

The frame 20 of the attachment is fastened to the bed plate 21 of a sewing machine, with screws 22. From the frame 20 extends the journal bracket 23, which supports the journal pin 24, for the bell crank 25 with the 65 arms 26 and 27. The arm 26 has a forked end 28 which straddles a screw 29, that extends from a collar 30, supported on the needle bar 31 of the sewing machine. To the needle bar is secured the needle 32 in the ordinary manner.

A spur gear 33 is journaled on a journal pin 34, that extends from the frame 20. It has the gear teeth 35 extending from its circumferential edge, and the ratchet teeth 36 70 75 projecting from its upper face.

A pin 37 extends from the arm 27 of the bell crank 25, and on the latter is journaled a pawl 38 with the hook end 39, which latter can engage with the ratchet teeth 36. A 80 spring 40 extends between the arm 27 and journaled end of the pawl 38. The pawl has a pin 41 extending from its side.

From the frame 20 extends the journal bracket 42 which supports the journal pin 43 85 for the ratchet interrupter arm 44, that has the lug 45 extending from its free end, and the said lug is located to normally ride on the upper face of the smooth portion of the spur gear 33. Ratchet interrupter pins 46 are 90 screwed into the upper face of the wheel 33, located so as to engage with the lug 45 when operating the said attachment.

A lug 47 extends up from the frame 20, into which is secured a journal pin 48 for the link 95 49, which latter carries the journal pin 50, for the L shaped operating arm 51.

A journal pin 52 is fastened to and extends up from the frame 20. A sleeve 53 is supported on the pin 52, and is kept from vertical displacement by means of the screw 54, which can bear on a shoulder formed in said sleeve. At the lower end of the sleeve 53 are formed teeth constituting a pinion 55, which meshes with the teeth 35 of the spur gear 33. 100 The upper end of the sleeve 53 terminates in a guide 56 for the nut 57. Screwed into said nut is the journal pin 58, which latter can secure the said nut at different positions in the said guide, so that the distance be- 105 110

- tween the vertical axis of the pin 52 and the axis of the pin 58 can be varied. A collar 59 of the operating arm 51 is journaled on the journal pin 58. To the end 60 of the operating arm is secured the guide block 61 by means of the screws 68. A cross head 62 is adjustably clamped in different positions in the dovetailed guide 63 of the guide block 61, the cross head being suitably formed to fit the said guide. A screw 64 fits a threaded hole in the cross-head 62, and has shoulders 65 and 66 that bear against the upper and lower faces of the end 60 of the said L shaped operating arm 51. A slot 67 is formed in the said operating arm to allow the insertion of the screw 64. A milled head on the top end of the screw 64 allows the operator to turn the same, and thereby raise and lower the cross head 62 with its appurtenances.
- 20 From the cross head 62 is journaled the supporting arm 69 on the pin 70. A pillow block 71 extends from the supporting arm 69 which supports a screw, with the right handed threads 72, and the left 25 handed threads 73, the right hand end of the screw being supported in the journaled end of the supporting arm 69. Clamping jaws 74 bear on the supporting arm 69 and have threaded bosses 75 to engage with the threads 30 of the said screw. Each of the clamping jaws has formed therewith the corrugated clamping surface 76 which extends upwardly, from the lower face of the jaw for a portion of its thickness. The clamping surface is angular in contour so that each can clamp a button at two points of its circumference. A milled head 77 allows the turning of the screw, and collars 78 on the screw bear against the pillow block 71 maintaining the screw in place.
- 40 A cap 79 is secured to the pillow block 71, and it has a hook 80 which is engaged by a hook 81, secured to the pressure bar 82 of the sewing machine. A spring 83 extends from the cross head 62 and bears on the cap 79.
- 45 Below the supporting arm 69 is located the supporting plate 84, which is attached to guide block 61 with the screws 85. The plate 84 has the opening 98 to allow the needle to pass therethrough and coat with the other elements of the sewing machine. The supporting plate 84, and supporting arm 69 with its clamping jaws and other appurtenances constitutes a clamping device, for 50 the buttons and material on which they are to be sewed.
- A post 86 extends from the frame 20, and it carries the adjustable ratchet interrupter plate 87 having a longitudinal opening. A screw 88 in the post 86 allows the plate to be 55 clamped in the path of the hook end 39 of the pawl 38.
- In the lug 47 that extends from the frame 20 there is pinned an adjusting bar 90 with the bent over journal end 91. The bar is 60 held from displacement by the link 49 and

its free end bears against the guide 56, to maintain it in proper position after having been intermittently rotated. A spring 92 extends between said bar and the bracket 23.

To operate the invention, the goods to 70 which the buttons are to be sewed, are secured to the clamping device by placing them on the supporting plate 84, and the buttons are then placed between the clamping jaws 74, the latter being adjusted to the requisite 75 distance apart, so that the buttons will be gripped by the corrugated surfaces of said jaws, and made to bear on the said material. By this disposition of the buttons and material, slippage between the buttons and material is avoided, when the attachment is in 80 operation.

The diameter of the pinion 55 being one-fourth of the diameter of the spur gear 33 the former will make four revolutions when the 85 spur gear is making one revolution.

When the sewing machine is operating for each up stroke of the needle bar 31, the spur gear 33 will be moved through an angle equivalent to an eighth of a revolution, equal 90 to the displacement corresponding to two of the ratchet teeth 36 extending from the spur gear.

To sew a two hole button both interrupters are moved out of gear, that is to say the 95 ratchet interrupter plate 87 is moved to the right as shown in the drawings, so that the hook end 39 of the pawl cannot ride thereon, and the ratchet interrupter pins 46 are removed from the spur gear 33, so that they 100 will not actuate the swinging ratchet interrupter arm 44. At 91 is shown a two hole button with stitches 92.

If a four hole button is to be sewed to the material, it is first determined whether the 105 stitches for the four holes shall be at right angles to each other, as shown at 93 in button 94, or whether they shall follow one hole after another consecutively, as shown at 95 in button 96.

To sew the stitches at right angles to each other the interrupter plate 87 is kept out of gear as shown in the drawings, and the ratchet interrupter pins 46 are fastened to the spur gear, the number of them depending 115 upon the nature of the stitches to be sewed. If one of the pins 46 is located on the spur gear, then for one revolution of the said gear the needle bar makes eight double strokes or eight stitches for two of the holes 120 of the button that are diametrically opposite each other, for the next revolution the interrupter pin has actuated the ratchet interrupter arm 44 and the pawl during the action of said interrupter arm, instead of overlapping two teeth of the ratchet only actuates one, and the pinion with its guide and appurtenances is turned 90 degrees or one-quarter of a revolution, and as for each reciprocation of the pawl 38 the pinion is 125 130

moved a half a revolution, the effect will be to move the clamping jaws now in a direction at right angles to the direction thereof, before the interrupting pin causes the pinion to turn 90 degrees, then during the next revolution of the large spur gear, the stitches formed will be at right angles to the stitches formed in the previous revolution of the spur gear, and thus during each revolution of the large spur gear, the directions of the stitches will be changed.

When two ratchet interrupter pins are secured to the spur gear 33, it is evident that four stitches will be sewed in one direction, and four at right angles thereto for each revolution of the spur gear.

When four interrupter pins are secured to the spur gear, then there will be sewed two stitches in one direction, and then two at right angles thereto, for one-half a revolution of the spur gear.

When the ratchet interrupter pins are removed from the spur gear and the ratchet interrupter plate is placed in the path of the hook end of the pawl, then for each up stroke of the needle bar, the spur gear will be moved through an angle equal to one sixteenth of a revolution, the pawl moving the spur gear through the length of one of its ratchet teeth for each reciprocation of the pawl. This will move the pinion through one-quarter of a revolution, and the button will be sewed on the material in the perimeter line of the button hole, one hole after another as shown in Fig. 11.

Having described my invention I claim:

1. In a button sewing attachment for a sewing machine the combination of a frame, a pinion journaled on the frame, an operating arm over the frame and operated by the said pinion, a spur gear meshing with said pinion, ratchet teeth extending from the spur gear, a bell crank pivoted on the attachment, a pawl pivoted from an arm of the bell crank, a ratchet interrupter arm pivoted on the attachment, a pin extending from the pawl and located to engage with the ratchet interrupter arm, a lug extending from the latter arm bearing on the upper face of the spur gear, means on the spur gear to engage the said lug and thereby raise the interrupter arm and pawl, a supporting plate, connections between said plate and the operating arm, a bearing arm pinned over the supporting plate, means to vary the distance between the supporting plate and bearing arm, clamping jaws bearing on the bearing arm, and means to vary the distance between the clamping jaws.

2. In a button sewing attachment for a sewing machine the combination of a frame, a pinion journaled on the frame, an operating arm over the frame and operated by said pinion, a spur gear meshing with said pinion, ratchet teeth extending from the

spur gear, a bell crank pivoted on the attachment, a pawl pivoted from an arm of the bell crank, a ratchet interrupter arm pivoted on the attachment, a pin extending from the pawl and located to engage with the ratchet interrupter arm, a lug extending from the latter arm bearing on the upper face of the spur gear, means on the spur gear to engage said lug and thereby raise the interrupter arm and pawl, a supporting plate, connections between said plate and the operating arm, a bearing arm pinned over the supporting plate, means to vary the distance between the supporting plate and bearing arm, clamping jaws bearing on the bearing arm, a pillow block on the supporting arm, and a spring bearing on the pillow block to maintain the supporting arm in proper position.

3. In a button sewing attachment for a sewing machine the combination of a frame, an operating arm over the frame, means to move one end of the arm under the point of a needle of a sewing machine, to consecutively locate the button holes of a button under said point, a dovetailed guide block extending from the operating arm, a cross-head fitting in said guide block, means to secure the cross-head in various positions in the guide block, a bearing arm journaled in the cross-head, a pillow block extending from the bearing arm, a screw having a right and left handed thread over said bearing arm, the said screw having a bearing between the right handed and left handed threads thereof, the said bearing supported in the said pillow block, one end of the screw supported in a bearing at one end of the bearing arm, and a head at the other end of the screw, a clamping jaw supported on the right handed thread of the screw and upon the bearing arm, a second clamping jaw supported on the left handed thread of the screw and bearing on the bearing arm, and a spring extending from the cross-head and bearing on the pillow block.

4. In a button sewing attachment for a sewing machine the combination of a frame, an operating arm over the frame, a clamping device extending from one end of said arm, a spur gear journaled on the frame, ratchet teeth extending from the spur gear, connections between the spur gear and the operating arm, a bell crank journaled over the frame, means to swing the bell crank, a pawl journaled from one arm of the bell crank and located to engage with the said ratchet teeth, a ratchet pawl interrupter pivoted on the attachment, means to engage the interrupter with the pawl, means to raise the interrupter and thereby disengage the pawl from said ratchet teeth and allow the pawl to skip a ratchet tooth when moving over the same.

5. In a button sewing attachment for a sewing machine the combination of a frame, an operating arm over the frame, a clamping

- device extending from one end of the said arm, a spur gear journaled on the frame, ratchet teeth extending from the upper face of the spur gear connections between the 5 other end of the arm and the spur gear, a bracket extending from the frame, a bell crank journaled from the bracket, one arm of the bell crank actuated by the needle bar of a sewing machine, a pawl journaled from the 10 other arm of the bell crank, the hook end of the pawl engaging the ratchet teeth extending from the spur gear, a pawl interrupter plate adjustably clamped in the path of the hook end of the pawl.
- 15 6. In a button sewing attachment for a sewing machine the combination of a frame, an operating arm over the frame, a clamping device to hold a button and a material to which it is sewed, extending from one end of 20 said arm, a spur gear journaled on the frame, ratchet teeth extending from the spur gear, connections between the spur gear and the operating arm, a bracket extending from the frame, a journal pin secured to the bracket, a 25 bell crank supported on the journal pin, one arm of said crank engaged with the needle bar of a sewing machine, a pawl journaled to the other arm of the bell crank, a spring extending between the journaled end of the 30 pawl and latter arm of the bell crank, so that the free end of the pawl tends to bear on the said ratchet teeth, a pin extending from the pawl, a pawl interrupter pin extending from the upper face of the spur gear, a second 35 bracket extending from the frame, a pawl interrupter arm journaled from the latter bracket, a lug extending from pawl interrupter arm bearing on the face of the spur gear, and in the path of the pawl interrupting pins.
- 40 7. In a sewing attachment for a sewing
- machine the combination of an operating arm journaled thereon, a clamping device connected with the operating arm, a bell crank journaled on the attachment, one arm of the bell crank connected with the needle bar of a sewing machine, a spur gear journaled on the attachment, ratchet teeth extending from the spur gear, a pawl pinned to the bell crank and located to engage with ratchet teeth, a ratchet pawl interrupter on the attachment in the path of the pawl, so that the pawl will slip one of the ratchet teeth each time it engages with another of said ratchet teeth.
8. In a button sewing attachment for a sewing machine the combination of a frame, a lug extending from the frame, a link journaled on the lug, an operating arm pinned to the link, a clamping device extending from one end of the operating arm, a spur gear journaled from the frame, a pinion journaled on the frame and meshing with the spur gear, means to intermittently rotate the spur gear, a guide extending from the pinion, a nut supported in said guide, a journal pin screwed in the nut to clamp the latter in different positions in the said guide, a collar extending from the operating arm supported on the journal pin screwed into the nut, an adjusting bar fulcrumed in the lug extending from the frame, and bearing against the guide extending from the pinion, a spring attached to the adjusting bar which tends to hold the said bar against the said guide.
- Signed at New York, in the county of New York and State of New York this 9th day of March A. D. 1906.
